UNITED STATES PATENT OFFICE.

ERNEST G. BRUCKMAN, OF NEW YORK, N. Y.

DESIGN FOR A CASING FOR AUTOMOBILE-RADIATORS.

52,053.

Specification for Design.

Patented May 28, 1918.

Application filed May 20, 1916. Serial No. 98,959. Term of patent 3½ years.

To all whom it may concern:

Be it known that I, ERNEST G. BRUCKMAN, a citizen of the United States, residing at New York city, in the county and State of New York, have invented a new, original, and ornamental Design for a Casing for Automobile-Radiators, of which the following is a specification, reference being had to the accompanying drawings, forming a part thereof, in which—

Figure 1 is a front elevation of a casing for automobile radiators made in accord-

ance with my invention. Fig. 2 is a side elevation; and Fig. 3 is a plan view thereof.

I claim:

The ornamental design for a casing for automobile radiators, as shown.

In witness whereof, I have hereunto set my hand in the presence of two subscribing witnesses, this 18th day of May, 1916.

ERNEST G. BRUCKMAN.

Witnesses:

M. L. KELLY,
P. F. SONNEK.
